HIGH FREQUENCY OSCILLATOR TUBE

Nyman Levin, Finchley, London, England, assignor to Radio Corporation of America, a corporation of Delaware

Application May 20, 1939, Serial No. 274,721
In Great Britain May 23, 1938

2 Claims. (Cl. 250—27.5)

This invention relates to high frequency oscillators and more particularly to electronic oscillator tubes of the type in which oscillations are obtained by causing electrons to pass through an apertured electrode so as to cause oscillatory fluctuations in the energy induced in said apertured electrode as a result of electron movement towards, through, and then away from said apertured electrode.

The object of the invention is to provide improved electronic oscillators which shall be capable of delivering higher power at greater efficiency and which shall be more immune from frequency change as an undesired result of modulation than are known comparable electronic oscillators.

In the following description reference will be made to the accompanying drawing in which

Figure 1 illustrates diagrammatically certain basic principles of electronics, and

Figs. 2 and 3 illustrate two forms of electron tube structure which I have found useful in carrying out the invention.

Figures 4 and 5 show electron discharge devices incorporating my invention provided with solenoids of different shapes for focusing the electron beam along the axis of the electron discharge device.

One of the best known forms of electronic oscillator is the so-called Barkhausen-Kurz or Gill-Morell oscillator and it will be of assistance in understanding the present invention to consider first the action of this oscillator. The usual arrangement of Barkhausen-Kurz or Gill-Morell oscillator comprises a triode whose grid is maintained at a high positive potential with respect to the cathode and plate. In use a stream of electrons is accelerated away from the cathode towards the grid and plate. Some of the electrons pass right through the grid and are then decelerated, stop, reverse in direction and again approach the grid under the influence of the grid field. Of these electrons a proportion will pass through the grid in the opposite direction and then be decelerated, stopped, and accelerated back towards the grid by the grid field. Thus an electronic oscillation takes place about the grid and oscillations will be obtained and variation in the energy in the positive grid circuit will occur by reason (it is believed) of fluctuations in the energy induced in the grid by electrons accelerated towards it, forced through it, and decelerated beyond it. This form of electronic oscillator has, however, two important defects: (a) the application of modulating potential to the triode to effect amplitude modulation

of the oscillations generated produces also a substantial undesired effect upon the frequency generated, and (b) the efficiency and available oscillatory power are low. The former defect arises by reason of the fact that the electron velocity in the tube is comparatively low and is, therefore, strongly affected by modulating potentials, and, of course, the periodicity of electron "swing" about the grid (the main factor in determining the frequency) is a function of the electron velocity. The cause of the second defect will best be appreciated by imagining the triode to be constituted as represented in the accompanying Fig. 1 by a cathode in the form of a flat sheet 1, a plate in the form of a parallel flat sheet 2, and an open mesh flat grid of parallel wires 3 mid-way between and parallel to the two sheets and equally positive with respect to both. Now neglecting space charge effects, the equi-potential surfaces in the system will, as represented by the dot and dash lines, run parallel to the three flat electrodes. Consider any point P on the cathode which is directly opposite a point in the middle line of the space between two adjacent grid wires. The only electrons from this point which will pass through the grid 3 will be the small proportion following paths lying in a narrow (approximate) cone C represented in broken lines and having its apex at the said point P on the cathode and no wider, at the grid, than the space between the said two adjacent grid wires. The most favorably situated points on the cathode for projecting electrons through the grid are those which are directly opposite points in a middle line of a space between two adjacent grid wires. Moreover, as regards those electrons in the (approximate) cone which pass through the grid and which are decelerated, stopped, reversed by the grid-anode field, it is clear that only a small proportion of these will pass through the grid on the return journey, for the equi-potential surfaces will cause the "return electron" cone to spread out into a wide angle (approximate) cone indicated, in part, by the more divergent dotted lines. Thus the action proceeds, only a small proportion of the electrons which pass through the grid in one direction succeeding in passing through the grid in the next, oppositely directed "swing." It is for this reason that the efficiency and available power are so small in known Barkhausen-Kurz and Gill-Morell oscillators despite attempts to increase cathode emission and to use open mesh grids. Hence, the proportion of the total cathode emission actu-

ally contributing to the oscillation generation remains small.

The present invention seeks to avoid the above described defects and limitations.

According to this invention an electronic oscillator comprises means for generating a sharply defined beam or jet of electrons, an apertured electrode or electrode system, means for causing the electrons in the beam to pass back and forth a plurality of times through the aperture (if there is only one) or (preferably) to pass in succession through the apertures (if there is a plurality) and means for re-focussing the beam in the plane of the aperture, or each aperture (as the case may be) each time it passes through. It is not considered advisable to pass the beam back and forth through the same aperture each time as the high space charge due to the concentration will tend to destroy the focus. It is far preferable to employ a plate with a number of apertures, or a series of plates each with one or more apertures, and all at the same potential. The focussing means may be magnetic or electrostatic, or a combination of both may be employed. The apertured plate or plates—the anode system of the oscillator—may be either positively or negatively biased. In use the electron beam makes a series of aperture transits, the focus of the beam becoming necessarily wider at each transit due to unavoidable distortion in the focussing system. In practice, however, with careful construction and design, it is possible to obtain a large number of transits before the focus becomes so wide as to result in no appreciable gain in efficiency.

In the embodiment illustrated in Fig. 2 there is employed an electron beam projection system consisting (in the order stated) of a narrow cylindrical cathode K, a modulating or intensity control electrode G, an accelerating anode AA and a concentrating electrode S. Each of the last three electrodes is in the form of a slotted plate with a narrow elongated slot corresponding approximately with the length and diameter of the cathode. The three plates are adjacent one another and parallel to one another and the cathode, the slots being aligned with one another and with the cathode. A slotted anode SA is mounted parallel to the three slotted electrodes already mentioned, the distance of this anode from the concentrating electrode S being relatively great as compared to the distance of the concentrating electrode from the accelerating anode AA. The slotted anode is provided with a plurality of similar slots AS₁, AS₂, AS₃, . . . and so on, which are parallel to one another and one of which—the end one AS₁ in the construction now being described—is substantially aligned with the slots in the three electrodes G, AA, S, adjacent the cathode. Each slot in the slotted anode is a little longer than and somewhat wider than the length and diameter (respectively) of the cathode. It will be appreciated that the dimension of the slotted anode in a direction at right angles to the lengths of the slots therein is a great deal more than the corresponding dimensions of the other three slotted electrodes for the slots in the slotted anode are equally spaced well apart. In other words, the slotted anode projects well to one side of what may be termed the electron gun. Insulated from the concentrating electrode S and in the same plane therewith is an additional plate-like electrode AP which extends over the length of the projecting portion of the slotted anode. On the opposite

side of the slotted anode, i. e. on the side thereof remote from the said additional electrode AP is a further plate-like electrode PP of about the same size as the slotted anode and parallel thereto, said slotted anode SA being equi-distant from the additional electrode AP and the further electrode PP. A series of magnetic focussing fields each running parallel to the directions of length of the slots, is generated by means of magnets 5 the pole pieces of which are indicated in dotted circular lines, so as to thread the discharge space between the further and additional electrodes, there being as many fields as there are slots in the slotted anode, each threading the space in 10 the neighborhood of a slot. Any two adjacent fields are in opposite directions. These fields may be generated by a sectionalized winding the sections being alternately reversed and shielded from one another by soft iron dividing plates. 15 The slotted anode SA may be either positive or negative with respect to the additional and further electrodes; in the former case, the two latter electrodes may be cathode potential, while in the latter case, they must be positively biased. 20 In use, with the above arrangement, a sheet like beam of electrons is projected from the projection system K, G, AA, S, through the first slot AS₁ in the slotted anode and then bends round more or less cycloidally as indicated by the 25 broken line, to pass through the second slot AS₂ after which it again bends back more or less cycloidally to pass through the third slot AS₃ . . . and so on, passing through all the slots 30 in succession until it is finally taken up on a suitable positive electrode. The magnitude and electrostatic conditions are such as to give a series of beam foci one at each slot in the slotted anode, and accordingly high efficiency is obtained as compared to a normal Barkhausen- 35 Kurz or Gill-Morell oscillator tube. This arrangement may be modified by reflecting the beam electrostatically, instead of magnetically, to cause it to travel to and fro through the successive slots in the slotted anode. 40 In a modification shown in Fig. 3, purely electrostatic focussing without reflection is employed. Here there is an electron beam projection system, as above described, and comprising a cathode K, a modulating electrode G, an accelerating anode AA, and a concentrating electrode S is 45 arranged to face the first, SA₁, of a series of slotted anodes SA₁, SA₂, . . . , each in the form of a plate with a slot corresponding in size to the cathode. The slotted anodes are parallel and 50 behind one another with their slots aligned with the slots in the electrodes of the beam projection system. These anodes are equally spaced by a distance equal to the distance between the first of them, SA₁, and the concentrating electrode S. The discharge space between the concentrating electrode and the first slotted anode is surrounded by two tubular electrodes 1T₁, 1T₂, placed edge to edge and a similar pair of electrodes 2T₁, 2T₂, 3T₁, 3T₂, surrounds the space 55 between each successive pair of slotted anodes. That one of each pair of tubular electrodes nearer the cathode is maintained at cathode potential and the other at slotted anode potential so that the said pair acts as an electron lens system to 60 give a focus of the electron beam at the slot of a slotted anode, the electrodes at cathode potential providing at the same time a decelerating force on the electron beam. Thus the beam passes in succession through the slotted anodes 65 being brought to a focus at each slot. The cross- 70

sectional shape of this whole electrode system may take any of a variety of forms, e. g. circular or rectangular. In the former case the tubular electrodes would, of course, be cylindrical and in the latter case rectangular. If desired, the slotted intermediate plates SA1, SA2, may be at cathode potential, the beam still being focussed at each slot.

The embodiment of Fig. 3 may be modified by replacing the electrostatic lenses—the pairs of tubular electrodes—by short magnetic coils outside the envelope housing the electrode system, or by a long uniform magnetic coil outside the envelope and extending the whole length of the tube, as in Figures 4 and 5 respectively. In the former case the coils can be corrected for rotation of the line focus by the method—well known per se—of reversing the current in the second half of each coil. Alternatively the slots in the slotted anodes may be not aligned but rotated, from anode to anode, according to the rotation produced by each coil. In the latter case the anodes must be placed at the nodes of the beam, the current through the coil being such as to produce the number of nodes required. In this arrangement no rotation is produced. In both these cases a decelerating electrode should be provided mid-way between the slotted anodes. These decelerating electrodes may be in the form of slotted plates, the slots being wider than those

in the slotted anodes, or in the form of open ended cylinders or rectangularly sectioned tubes.

I claim:

1. An electron discharge device having a cathode for supplying electrons and means adjacent the cathode for focusing the electrons into a well defined beam, a plane electrode spaced from said cathode and having a plurality of apertures therein, said electrode being positioned with one of said apertures in alignment with said electron beam, and an electrode positioned in spaced relationship on each side of said apertured electrode, and means for inducing magnetic fields through said apertures and parallel to the plane apertured electrode.

2. An electron discharge device having a cathode for supplying electrons and means adjacent the cathode for focusing the electrons into a well defined beam, a plane electrode spaced from said cathode and having a plurality of apertures therein, said electrode being positioned with one of said apertures in alignment with said electron beam, and an electrode positioned in spaced relationship on each side of said apertured electrode, and electromagnetic means for inducing oppositely directed magnetic fields within said apertures, said oppositely directed fields alternating along the length of said apertured electrode.
